TOBACCO TREATMENT

Paul La Frone Magill, Ransomville, N. Y., assignor to E. I. du Pont de Nemours & Company, Wilmington, Del., a corporation of Delaware

No Drawing. Application April 15, 1936,
Serial No. 74,599

7 Claims. (Cl. 131—31)

This invention relates to the treatment of tobacco and more particularly to a method for preserving cured tobacco and inhibiting its drying out.

To maintain the desired smoking quality of tobacco it is necessary that a certain moisture content of tobacco be maintained. Also, in the manufacture of cigars and in other tobacco processing operations, it is necessary to maintain the tobacco in a moist condition in order that the leaves will have the proper flexibility. It has been common practice heretofore to treat tobacco with glycerin, adding a small amount within the range of 1 to 10%, e. g., around 5% by weight of tobacco. The hygroscopic properties of glycerin inhibits drying out to some extent.

The storage of humidified tobacco under some conditions results in an attack by molds or other fungi. Tobacco which has been treated with glycerin is quite susceptible to such fungus attack.

An object of the present invention is to provide an improved method of treating tobacco whereby drying out is inhibited and at the same time the tobacco is preserved against fungus attack and other spoilage. Other objects will be hereinafter apparent.

I have discovered that by applying to tobacco a small amount of formamide, the tobacco may be preserved from the attack of fungus and like pests and at the same time the hygroscopic nature of the formamide inhibits drying out of the tobacco. I have further found that the inhibition of drying out by the use of formamide is greater than that obtained by using glycerin for the same purpose.

In practicing my invention I apply from 1 to 10%, usually around 5%, by weight of formamide to the tobacco by any suitable means. The formamide may be applied at any desired stage in the processing of the tobacco; for example it may be applied to the leaves directly after they have been cured or during some stage of the curing process or it may be applied after the leaves have been cut. Formamide may be applied as such or in the form of an aqueous solution. During the processing of tobacco it is common practice to humidify the leaves by spraying with water at certain stages of the process. In the application of my invention to such curing process, I prefer to spray the tobacco with water in which a small amount of formamide has been dissolved.

Formamide in the pure state is a colorless mobile liquid boiling at around 200° C., having good chemical stability at temperatures below its boil-

ing point, and very soluble in water. It does not impart any undesirable odor, taste or other undesirable properties to tobacco treated with it; nor does it have any adverse effect on the smoking quality of the tobacco.

The following example illustrates the superior effect of formamide in inhibiting the drying out of tobacco.

Example

Chopped up cured tobacco was divided into three portions, one of which was sprayed with an aqueous solution of glycerin, another sprayed with an aqueous solution of formamide and the third left untreated. The treated portions contained about 5% by weight of the glycerin or formamide respectively. The three samples were simultaneously exposed to the air at room temperatures for 18 hours. Each sample was weighed before and after the exposure time in order to ascertain the loss in moisture content by drying. The results obtained are tabulated below:

Percentage of moisture lost on standing 18 hours

	Percent
Untreated tobacco	26.7
Glycerin treated tobacco	26.6
Formamide treated tobacco	25.6

The two samples of tobacco treated with formamide and glycerin were placed in two separate beakers loosely covered with a watch glass and set aside in the dark for two months. At the end of this time the sample which had been treated with glycerin was heavily encrusted throughout with a mass of white fungus. The sample treated with formamide did not show any evidence of fungus and appeared in every way identical with the untreated tobacco.

I claim:

1. A process for treating tobacco which comprises applying formamide thereto.
2. A process for treating tobacco which comprises applying an aqueous solution of formamide thereto.
3. A process for treating tobacco which comprises applying formamide thereto in an amount equal to 1 to 10% by weight of the tobacco.
4. A process for treating tobacco which comprises applying formamide thereto in an amount equal to about 5% by weight of the tobacco.
5. A composition of matter comprising tobacco and formamide.
6. A composition of matter comprising tobacco and 1 to 10% by weight of formamide.
7. A composition of matter comprising tobacco and about 5% by weight of formamide.

PAUL LA FRONE MAGILL
